J. M. SULLIVAN

DAMPER REGULATOR

Filed Apr. 16, 1921

UNITED STATES PATENT OFFICE.

JOSEPH M. SULLIVAN, OF DETROIT, MICHIGAN.

DAMPER REGULATOR.

Application filed April 16, 1921. Serial No. 461,931.

To all whom it may concern:

Be it known that I, JOSEPH M. SULLIVAN, a citizen of the United States of America, residing at Detroit, in the county of Wayne 5 and State of Michigan, have invented certain new and useful Improvements in Damper Regulators, of which the following is a specification, reference being had therein to the accompanying drawings.

10 This invention relates to a damper regulator for boilers and has special reference to that class of automatic damper regulating devices which are actuated by extreme pressure to adjust a damper controlling the 15 draft to the combustion chamber of the boiler and consequently the generation of steam by the boiler. I am aware of such devices being used and the regulation of a damper in two extremes, that is, the damper 20 is either open or closed and there is no intermediate position to which the damper is adjusted, consequently there is either a high or low pressure of steam in the boiler, in one instance probably a waste of fuel, and in 25 the other instance not sufficient pressure for power.

My invention aims to provide a damper regulating device by which the damper may be minutely adjusted in accordance with a 30 boiler pressure, thus insuring a positive and uniform regulation without any abrupt changes in boiler pressure.

My invention further aims to provide an intercepting valve that may be easily and 35 quickly installed in damper regulators already in use, so as to convert such extreme damper regulators to regulators permitting of a wider range of damper adjustment.

My invention also aims to improve 40 damper regulator devices by certain mechanical refinements which lend greater sensitiveness to the devices, facilitates manufacture, and afford a higher degree of efficiency in the automatic control of boilers, 45 furnaces and other heating apparatus.

My invention will be hereinafter described and then claimed, and reference will now be had to the drawings, wherein

50 Figure 1 is a front elevation of the damper regulating device, partly broken away and partly in section, showing its relation to a damper and parts of the installation conveniently arranged for the sake of illustration;

55 Fig. 2 is a vertical transverse sectional

view of the regulator valve taken on a plane at a right angle to the section of the valve shown in Fig. 1;

Fig. 3 is a horizontal sectional view of 60 the regulator valve; and

Fig. 4 is a cross sectional view taken on the line IV—IV of Fig. 1.

In the drawing, the reference numeral 1 denotes an instrument board that may hold various instruments, for instance pressure 65 gauges 2, and suitably attached to said instrument boards as at 3, is a horizontally disposed diaphragm casing 4 to which is connected a pipe or conduit 5. This pipe or conduit supplies steam to the diaphragm casing 4 at boiler pressure and consequently 70 leads from the boiler (not shown).

Suitably mounted in the diaphragm casing 4 is a diaphragm 6 having a central wear or contact member 7 normally engaging the knife edge or contact point 8 of a lever socket 9, said lever socket having its bifurcated inner end or short arm 10 apertured, as at 11, to receive knife edge pivot members 12 carried by the diaphragm casing 4.

The lever socket 9 is limited in its movement relative to the diaphragm casing 4 by a set screw 13 carried by the lever and extending through an apertured lug or bracket 75 14 of the diaphragm casing 4, and detachably mounted in the lever socket is a long lever 15 disposed in a plane parallel to the instrument board 1.

On the outer end of the lever 15 is an 90 adjustable suspension member 16 for a weight 17, said weight maintaining the contact point 8 of the lever socket 9, constantly in engagement with the contact member 7 of the diaphragm 6, so that steam pressure 95 in the diaphragm casing 4 may elevate the outer end of the lever 15.

Extending outwardly from the instrument board 1 is a stud 18 and adjustable on said stud is the apertured boss 19 of the 100 regulator valve body 20. The manner of supporting the valve body 20 permits of it being correctly positioned relative to the lever 15 and also facilitates connections with said valve body for purposes which 105 will hereinafter appear.

The valve body 20 is provided with a longitudinal central bore 21 and in said valve body, about the bore 21 are an inlet chamber 22, a discharge chamber 23, and 110

an exhaust chamber 24, said exhaust chamber communicating with top and bottom chambers 25 and 26, as best shown in Fig. 2.

Mounted in the bore 21 of the valve body 20 and detachably retained therein by end plugs 27 and 28 is a take-apart tubular liner 29 provided with lateral ports 30 and 31, the former communicating with the discharge chamber 23, and the latter communicating with the inlet chamber 22, this being accomplished through the medium of ports in the walls of the bore 21.

The plug 28 is hollow and communicates with the bottom chamber 26 of the valve body, said plug having a discharge pipe or conduit 32. The plug 27 is tubular and communicates with the top chamber 25 of the valve body 20, and slidable in the plug 27 and the liner 29 and extending into the plug 28 is a hollow valve stem 33 provided with chambers 34 and 35. The chamber walls 34 have opposed ports 36 and 37 and the chamber walls 35 have opposed ports 38 and 39. Since the valve stem 33 is slideable in the valve, the ports 37, 38 and 36 may be blanked or closed by walls of the liner 29, but the ports 36 are adapted to constantly communicate with the top chamber 25 of the valve body.

Communicating with the chamber 22 of the valve body 20 is a pipe or conduit 40 adapted to admit water or a motive liquid to the chamber 22. Since the valve is used as a regulator in connection with a boiler, it is preferable to use water under pressure as a motive liquid for performing work, as will hereinafter appear.

The discharge chamber 23 of the valve body is connected by a pipe or conduit 41 to the top of a vertically disposed cylinder 42 suitably supported from the instrument board 1. The bottom of the cylinder 42 has an atmospheric port 43 and slidable in the top of the cylinder is a piston rod 44 provided with a conventional form of piston 45 within the cylinder 42. The cylinder 42 is adapted to receive the motive liquid from the valve body 20 and such motive liquid and the cylinder constitute power means for adjusting a damper.

To illustrate how a damper may be adjusted, I show a flue, stack or conduit 46 having a shutter or damper 47 therein. The damper 47 is on a pivot 48 provided with 55 a sheave 49 and trained over the sheave 49 is a flexible member 50, as a cable, said flexible member being trained over other sheaves 51 and having its ends attached to a weight or counterbalance 52 and to the end of the piston rod 44. The weight or counterbalance 52 has a tendency to constantly open the damper 47 and by lowering the piston 45 within the cylinder 42, the damper 47 may be adjusted towards a closed 60 position or completely closed.

Slidably mounted on the lever 15 and secured in a fixed position relative thereto is a bracket 53 provided with a side bearing 54 for a rock shaft 55. One end of the rock shaft 55 has a cross head 56 and slidable 70 in said cross head is a block 57 having a tongue and groove connection with the cross head so that it will not become laterally displaced but may freely slide in the cross head. The block 57, however, may be fixed relative 75 to the cross head by a set screw 58, and pivotally connected to the outer face of the block 57 is an arm 59 to which the valve stem 33 is loosely connected by a link 60. The outer end of the arm 59 is connected 80 by a link 61 to the lever 15, and said arm is adapted to occupy a position normally parallel to the lever 15.

Attached to the opposite end of the rock shaft 55 is a depending crank 62 and the lower end of said crank is connected by a link 63 to a coupling link 64. The coupling link 64 forms part of a flexible member or cable 65 trained over and under sheaves 66. One end of the cable 65 is attached to the upper end of the piston rod 44, and the opposite end of the cable 65 is provided with a weight or counterbalance 67. The weight 67 cooperates with the weight 52 in maintaining the piston 45 intermediate the ends 95 of the cylinder 42 with the damper 47 in what may be considered a midway position, so that it may be either adjusted towards a full open position or a full closed position, depending on the movement of the 100 piston 45 in the cylinder 42. For the purposes of explaining the operation of the regulator, the midway position of the damper 45 may be considered normal with the boiler or boilers operating at a desired 105 steam pressure.

By reference to the valve in Fig. 1 it will be noted that the intermediate ports 37 and 38 of the valve stem 33 are blanked by the walls of the liner 29, and assuming that the 110 pressure of a boiler increases, the diaphragm 6 will be expanded or flexed upwardly to raise the lever 15 and the valve stem 33 which is articulated with said lever by the arm 59, link 61, bracket 53 and cross head 56.

When the valve stem 33 is raised, the ports 37 and 36 may be blanked by the liner 29 and the plug 27, but the ports 38 and 39 are brought into action. The port 39 will establish communication between the inlet chamber 22 and the discharge chamber 23 through the medium of the chamber 35 and port 38, permitting the water or motive liquid, under pressure, to enter the pipe or conduit 41 and the upper end of the cylinder 42. The water will shift the piston 45 downwardly within the cylinder 42 and shift the damper 47 toward a closed position 125 reducing the draft in the flue 46 consequent- 130

ly reducing steam pressure at the boiler or
boilers.

Since motive liquid is admitted to the cylinder 42 there would be a full stroke of the 5 piston 45 and complete closing of the damper 47 if no provision were made for intercepting the stroke of the piston 45 and consequently the full closing movement of the damper 47. The intercepting action 10 takes place after the initial movement of the piston 45 and such action is brought about by the weight 67 shifting the crank 62 to rock the shaft 55 and turn the cross head 56 at an angle to its original plane. That end 15 of the cross head adjacent the valve body 20 will be lowered causing the block 57 to shift and lower the arm 59. Since this arm is articulated with the valve stem 33, the valve stem will be lowered, thereby shutting off 20 the motive liquid to the cylinder 42 and causing a cessation in the downward movement of the piston 45. This takes place before the damper 47 has had a chance to fully move to a closed position, therefore its movement 25 has been intercepted and the damper but partially closed.

Lowering of the valve stem 33 has retained the motive liquid within the cylinder 42 so as to hold the piston 45 in a shifted position, against the action of the weight 52, which has a tendency to open the damper 47.

Considering a reverse operation of the regulator device and assuming that boiler pressure has dropped below normal, there is 35 a reduced pressure in the diaphragm casing 4 and consequently the diaphragm 6 is flexed downwardly and the lever 15 lowered. This lever, through the medium of the bracket 53, link 61 and arm 59 causes the 40 valve stem 33 to be lowered, placing the valve stem ports 37 in communication with the discharge chamber 23, consequently the motive liquid within the cylinder 42 is released and discharges through the valve stem 45 into the top chamber 25, exhaust chamber 24, bottom chamber 26 and out through the exhaust pipe or conduit 32. Since the 50 motive liquid within the cylinder 42 has been released the weight 52 causes the pivot 48 to turn and start to open the damper 47, but before the damper can travel very far, its movement is intercepted. This is accomplished by the crank 62 being shifted in an opposite direction to that previously described, so that the cross head 56 will be

tilted and the pivoted end of the arm 59 raised, thus causing the valve stem 33 to be raised and restored to its normal position, cutting off the exhaust of motive liquid from the cylinder 42.

What I claim is:—

1. The combination of a damper, a valve adapted to be adjusted and by such adjustment effect movement of said damper, an arm for adjusting said valve, a slide head at 65 one end of said arm, pressure actuated means adapted to bodily move said arm and said slide head to adjust said valve in one direction, and gravity means operable independent of the first mentioned means adapted to cause said slide head to slide and adjust said arm so that said valve is adjusted in an opposite direction.

2. In a damper regulator, a valve by 70 which the regulation is attained, an adjustable valve stem, a lever adapted to adjust said valve stem, an arm having one end supported by said lever and adapted to be moved thereby to adjust said valve stem in one direction, a pivoted crank supported from said lever, a head movable with said crank, and a slide block carried by said head and articulated with the opposite end of said arm adapted for moving said arm to adjust the valve stem in an opposite direction.

3. In a damper regulator, the combination of a damper, a sheave for adjusting said damper, articulated cables with one of said cables trained over said sheave, weights suspended by said cables as counter-balance 90 means for said damper adapted to be unbalanced and cause either opening or closing of said damper, fluid actuated means adapted to unbalance said counterbalance means and cause said damper to start to close, a valve controlling the operation of said fluid actuated means, pressure actuated means adapted to adjust said valve to set said fluid actuated means in operation, and intercepting means actuated by the unbalancing of 95 said counterbalance means adapted to cause adjustment of said valve and a cessation in the operation of said fluid actuated means.

In testimony whereof I affix my signature in presence of two witnesses.

JOSEPH M. SULLIVAN.
